UNITED STATES PATENT OFFICE.

WILLARD C. COUSINS, OF FERRUM, VIRGINIA.

DESIGN FOR AN INDICATOR.

SPECIFICATION forming part of Design No. 29,492, dated October 18, 1898.

Application filed September 8, 1898. Serial No. 690,532. Term of patent 7 years.

To all whom it may concern:

Be it known that I, WILLARD C. COUSINS, a citizen of the United States, residing at Ferrum, in the county of Franklin and State of Virginia, have invented and produced a new and original Design for Indicators, of which the following is a specification.

This invention relates to a new and original design for an indicator; and it has for its object to provide a design of this character that shall be both useful and ornamental.

The leading feature of the design resides in an indicator having a rectangular bottle-shaped outline and provided with a central circular figure encircling a separate interior figure also having a rectangular bottle-shaped outline.

A minor feature of the design is the interior bottle-shaped figure, having a narrowed oblong portion or neck at one end, provided with a conical point and diametrically opposite V-shaped side projections.

In the drawing the figure is an elevation of an indicator embodying the herein-described design.

Referring to the accompanying drawing, the numeral 1 designates the main body of the indicator, having a rectangular bottle-

shaped outline and provided with a central circular figure 2.

The central circular figure 2 of the indicator-body 1 forms the boundary of a circular field, within which is located a separate interior figure 3, also of a rectangular bottle-shaped outline. The said interior bottle-shaped figure 3 is provided with an oblong portion 4, having parallel side edges and a straight end edge 5, opposite to which end edge the said figure is provided with inwardly-convergent inclined edges 6, from which is projected a narrowed oblong neck portion 7. The said narrowed oblong neck portion 7 of the bottle-shaped figure 3 is provided at diametrically opposite sides with the V-shaped projections 8 and beyond such projections with a conical or V-shaped point 9.

What is claimed is—

The design for an indicator, herein shown and described.

In testimony that I claim the foregoing as my own I have hereto affixed my signature in the presence of two witnesses.

WILLARD C. COUSINS.
